(57) **CLAIM**

The ornamental design for a hanger base for guitar, as shown and described.

DESCRIPTION

FIG. 1 is a perspective view of a hanger base for guitar showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof; and,

FIG. 8 is a perspective view thereof, showing the hanger connected to the base.

The broken lines in the drawings depict portions of the hanger base for guitar that form no part of the claimed design.
